(57) **CLAIM**

The ornamental design for a cup with inner ice compartment with lid, as shown and described.

DESCRIPTION

FIG. 1 is a perspective view of a cup with inner ice compartment with lid showing my new design;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.

The broken lines in the drawings are included for the purpose of illustration and form no part of the claimed design.
